FIG. 1

FIG. 2

INVENTOR

John B. Freysinger

UNITED STATES PATENT OFFICE

91,710

DESIGN FOR A BUCKLE

John B. Freysinger, New Britain, Conn., assignor
to North & Judd Manufacturing Company,
New Britain, Conn., a corporation of Connect-
icut

Application January 15, 1934, Serial No. 50,412

Term of patent 3½ years

To all whom it may concern:

Be it known that I, JOHN B. FREYSINGER, a citizen of the United States, and a resident of New Britain, in the county of Hartford, State of Connecticut, have invented a new, original, and ornamental Design for Buckles, of which the following is a specification, reference being had to the accompanying drawing, forming part hereof.

In the accompanying drawing:

Figure 1 is a front view of a buckle showing my new design;

Figure 2 is a sectional view on line 2—2 of Fig. I.

I claim:

The ornamental design for a buckle as shown.

JOHN B. FREYSINGER.
